UNITED STATES PATENT OFFICE.

HOMER METHOT, OF RED BANK, NEW JERSEY.

WASHING MACHINE.

1,402,634.

Specification of Letters Patent. Patented Jan. 3, 1922.

Application filed August 27, 1920. Serial No. 406,293.

To all whom it may concern:

Be it known that I, HOMER METHOT, a citizen of the United States, and a resident of Red Bank, in the county of Monmouth and 5 State of New Jersey, have invented a new and Improved Washing Machine, of which the following is a full, clear, and exact description.

The present invention relates to new and 10 useful improvements in washing machines, and it pertains more particularly to washing machines of the power-actuated type.

It is one of the primary objects of the present invention to construct a power washing 15 machine of the reciprocating plunger type in which the articles washed are subjected to varying amounts of pressure.

It is a further object of the invention to so 20 construct a washing machine of this type that the pressure of the plungers may be varied.

It is a further object of the invention to provide a pivoted platform for supporting the driving mechanisms of the plungers in such a manner that the plungers and their 25 reciprocating means may not be subjected to undue strain during their operation.

It is a further object of the present invention to provide a rotary tub which is movable with respect to the plungers in order that all 30 of the articles carried by the tub may be operated upon by said plungers.

It is a still further object of the present invention to supply washing fluid to the tub in a new and novel manner together with the 35 provision of an over flow for the tub, whereby a constant circulation of cleaning fluid through the tub is maintained.

With the above and other objects in view, reference is had to the accompanying drawings, in which—

Figure 1 is a view in elevation of a washing machine constructed and arranged in accordance with the present invention;

Fig. 2 is a vertical sectional view thereof;

Fig. 3 is a schematic view showing the relative positions of the plungers during the operation thereof;

Fig. 4 is a detail sectional view of a portion of the machine.

Referring more particularly to the drawings, the machine comprises a framework 5, preferably formed of suitable angle irons, and said framework is supported from a base 6, and is strengthened by means of a plural- 55 ity of angularly disposed braces 7 and trans- verse braces 8, it being understood that a

sufficient number of braces are employed to give the necessary rigidity to the framework.

Near the upper end of the vertical members of the frame 5 are two braces 10, there 60 being one of these braces on each side of the machine, and each of said braces has one of its ends extended as indicated by the reference character 11. Mounted in the extended end 11 of each of the braces 10, is a bearing 65 12, and mounted in the bearing 12, is a shaft 13. The reference character 14 designates a platform provided with a bearing 15 which surrounds the shaft 13 and forms means for pivotally mounting the platform.

Mounted on the platform 14 is a motor 16, and said motor 16 has its shaft extended as indicated by the reference character 17, and provided with a worm gear 18. This worm gear 18 meshes with a gear 19 carried on a 70 shaft 20, and said shaft is provided with a sprocket 21 of smaller diameter than the gear 19. Mounted in bearings 23 carried by the pivoted platform 14, is a crank shaft 25, and said crank shaft 25 is provided with a 75 sprocket 26. Passing around the small sprocket 21 on the shaft 20 and the sprocket 26 on the crank shaft 25, is a chain 22, and said chain forms the means by which the crank shaft is rotated from the shaft 20. 85

Rigidly secured to the transverse braces 8, as at 30, is a supporting member 31, and rigidly carried by the supporting member at its upper and lower edge, are brackets 32. Mounted in the brackets 32 are guide rods 90 33, in the present instance there being three sets of guide rods 33, as best seen in Fig. 2. These guide rods 33 are secured in place on the brackets 32 by means of cleats or the like 34, and these guide rods 33 form the support 95 for the mounting of cross heads 35. Each of the cross heads 35 is provided with two tubular leg members 36 adapted to surround their respective guides 33 to form the means by which the cross heads are reciprocatively 100 mounted. These cross heads are arranged side by side, and secured to each of the cross heads as at 38', is a vertically disposed shaft 37. By this arrangement it will be seen that there are two outside vertical shafts 37 and 105 one intermediate vertical shaft 37, and secured to the lower end of each of the outside shafts 37, is a plunger 38 of substantially circular form, while secured to the lower end of the central vertical shaft 37, 110 is a plunger 39, substantially elliptical in form. The purpose of forming the central

plunger elliptical in form will be hereinafter more fully set forth.

The upper end of each of the cross heads 35 is connected to the crank shaft 25, as indicated by the reference character 40, by means of connecting rods 40', in order that as the crank shaft 25 is rotated, the vertical shafts 35 will be given a reciprocatory movement and will be guided in such movement 10 by means of the guides 33 and the cross heads 35.

While the crank shaft 25 may be so formed as to have all of the shafts 37 reciprocate in the same direction in the preferred form of 15 the invention as illustrated, the crank members of the shaft 25 are spaced equi-distantly apart about the arc subscribed by said crank shaft, in which position of parts a successive action of the plungers is obtained rather 20 than a simultaneous action as in the aforementioned form where they operate in the same direction in unison.

Pivottally secured to the shaft 13 as by means of hinges 45, are arms 46, and said 25 arms 46 form the means for pivottally mounting a platform 47, said platform being disposed beneath the platform 14. Interposed between the free end of the platform 47 and the free end of the platform 14, is a coil 30 spring 48, and said coil spring 48 is placed under compression upon movement of the platform 47 in a direction towards the platform 14.

Two of the members of the frame 5 are extended as indicated by the reference character 49, and mounted in the extended ends of said frame, by means of a bearing 50, is a shaft 51. Mounted upon each end of the shaft 51, is a sprocket 52, and passing around 40 said sprockets 52 are chains 53. One end of each of these chains is attached as at 54 to the opposite sides of the platform 47 and carried by the opposite end of each of the chains, is a weight 55, the purpose of which 45 will be hereinafter explained.

Secured to one end of the shaft 51, is a sprocket 56, and passing around the sprocket 56, is a chain 57, which chain also passes around a sprocket 58 mounted on the opposite 50 side of the frame 5 and operated by means of a hand crank 59. The sprocket 58 is mounted on a shaft 60, and rigidly carried by said shaft 60, is a toothed gear 61. Pivottally mounted as at 62, to one of the 55 transverse braces 8, is a dog 63, and said dog 63 has a hooked end 64 adapted to engage between the teeth of the toothed gear 61.

The frame 5 is provided near its lower portion with transverse braces 65, and 60 mounted on said braces 65 is a trough 66, which trough 66 is provided with a discharge or outlet 67. Mounted above the trough 66, is a tub 70, and said tub 70 is so mounted as to be revoluble within the 65 frame 5.

To provide for revolubly mounting the tub 70, a transverse brace 71 is carried by the frame 5, and mounted on said transverse brace 71, is a bearing block 72. This bearing block 72 is hollow and has fitting therein 70 a sleeve member 73. This sleeve member 73 has rigidly secured thereto, as at 74, a circular rack 75, the purpose of which rack will be hereinafter described.

Mounted within the sleeve member 73 is 75 a tubular member 75', and said tubular member 75' is provided on its upper end with a flange 76. This flange 76 overlies the flange of the sleeve member 73 and is secured to the tub by means of bolts or the like 77. The 80 lower end of the flanged tubular member 75' is projected below the brace 71 as indicated at 80, and is externally screw-threaded to provide for the attachment of a collar 81. Secured to the tubular member 75', by 85 means of a collar 81, is a nipple 82, and secured to the nipple 82, by means of a collar 83, is an elbow 84. This elbow 84 is connected to a pipe 85, which pipe 85 is in turn connected to a T-coupling 86. Leading to 90 the T-coupling 86 is a pipe 87, the upper end of which is provided with a T-coupling 88, and leading into one side of the T-coupling 88, is a water supply pipe 89, and leading to the other side of the T-coupling is a steam 95 supply pipe 90. The water supply pipe 89 and the steam supply pipe 90 are controlled by valves 91 and 92, respectively, which valves control the admission of either water or steam, or both, to the pipe 87. 100 Leading from the opposite side of the T-coupling 86, is a pipe 93, and said pipe 93 is provided with a valve 94 operated by a rod 95 and hand wheel 96. Leading from the valve 94 is a drain 97, and by this 105 means it will be apparent that if the valves 91 and 92 are closed and the valve 94 is open, the tub will be drained of its liquid contents. The tub 70 is provided with two overflow pipes 98 and 99, the overflow 99 110 being positioned at a point nearer the top of the tub than the overflow 98, and these overflows are adapted to be closed by means of a plug 100.

As before stated, the circular rack 75 is 115 secured to the tub 70, and to provide for moving the tub in a step-by-step circular path, a dog or pawl 105 is adapted to successively engage the teeth of the rack 75. This dog or pawl 105 is pivottally secured 120 as at 106 to a lever 107, and said lever is in turn pivottally mounted as at 108, to the frame 5. Pivottally connected as at 109, to the dog or pawl 105, is a vertically extending rod 110, and said vertically extending rod 110 is pivottally secured as at 111 to one arm 112 of a bell crank lever, which is pivottally mounted as at 113 to one of the upper transverse braces 8. Pivottally secured as at 114, to the arm 115 of the bell crank lever, is a 130

rod 116, and said rod 116 is eccentrically connected at 117 to a rotating disk 119 mounted on the shaft 13. This shaft 13 is rotated from the crank shaft 25, by means of 5 a chain 120, said chain passing around a sprocket wheel 121 (Fig. 2) carried by the crank shaft 13, and a sprocket wheel 122 mounted on the crank shaft 25.

By this construction it is apparent that as 10 the rod 110 is reciprocated, the pawl 105 will be engaged with the several teeth 75 of the circular rack and will move the same in a circular direction and consequently moving the tub 70 likewise.

15 The device operates in the following manner:

Assuming that the articles to be washed have been placed in the tub 70, the valves 91 and 92 are opened to admit water and 20 steam to the pipe 87, and thence to the tub 70, said water entering the bottom of the tub and passing through the perforated false bottom therein. The motor 16 is now started, and through the medium of the 25 crank shaft 25, the plungers 38 and 39 will be given a vertical movement in contact with the articles being washed. As the plungers 38 and 39 move vertically into and out of engagement with the clothes, it will be seen 30 that through the medium of the pivoted dog 105 and the vertical rod 110 which causes said dog to successively engage the teeth of the circular rack 75, the tub will be rotated in a step-by-step manner, to present different surfaces of the articles being washed to the action of the plungers 38. As shown in 35 Fig. 3, it will be noticed that inasmuch as the central plunger 39 is oval, it will serve to engage the articles being washed at that 40 point where they are not engaged by the plungers 38 as the tub rotates beneath the plungers. As the tub rotates beneath the plungers, the plungers 38 being circular in 45 form, will leave portions of the articles being washed which would not be subjected to the action of the plungers were it not for the fact that the central plunger is oval in form, thus covering the space in the tub not covered by the circular plungers 38.

50 If in the operation of the plungers, it is desired to decrease the pressure with which they engage the articles being washed, it will only be necessary to disengage the hook end 64 of the dog 63 from the toothed gear 55 61, and by means of the operating handle 59 and the chain 57 rotate the shaft 51. Upon rotation of the shaft 51, the chain 53 will cause a lifting of the floating platform 60 47 and will place the spring 48 under compression. As the spring 48 is placed under compression, it will be seen that the upper floating platform 14 will be slightly elevated, and due to this elevation of the upper platform 14, the several plungers will not 65 engage the articles being washed until a

latter period in their stroke, and, therefore, the period of compression of the articles being washed will be lessened. If, however, the lower platform 47 is lowered thus lowering the upper platform 14, it will be seen 70 that the several plungers will engage the articles being washed at an earlier period in their stroke, and that therefore said articles being washed will be subjected to greater pressure than is the case where the platforms 75 are elevated. As the several plungers engage the articles being washed, it will be seen that the two floating platforms 14 and 47 will be rocked about their respective pivotal points when the limit of compression 80 has been reached, in order that the several parts of the mechanism may give way to a strain occasioned by the compression in the tub when the latter has reached its limit.

As the plungers 37 continue to operate in 85 contact with the articles being washed and the dirt is released therefrom, said dirt will float to the surface of the washing fluid and may be carried off either by the overflow 98 or the overflow 99 depending upon which of 90 these two overflows is opened to the interior of the tub.

While in the present instance the floating platforms 14 and 47 have been shown as 95 used in connection with a washing machine, it is obvious that they may be employed in the same manner in various types of machines wherein vertical plungers for the production of pressure are employed, and it is desired to regulate or vary the pressure 100 of the plungers.

From the foregoing it will be seen that the present invention provides a new and novel form of washing machine in which a plurality of vertically movable plungers adapted to exert pressure upon the articles being washed, are employed, said plungers being so constructed and arranged as to vary the pressure at which they operate on the articles subjected to the washing machine. 110

It will also be noted that by introducing the washing fluid to the bottom of the tub, and subsequently draining the same from the top thereof, the articles being washed are at all times subjected to clear and clean 115 washing fluid, the dirt being carried off from the top of the tub at a point above the articles being washed.

Claims:

1. A washing machine comprising a 120 frame, a washing receptacle, a plurality of plungers movable within said receptacle, a platform pivotally mounted in the frame, means for resiliently mounting said pivoted platform, and driving means for said plungers, said driving means being mounted upon the resilient pivoted platform. 125

2. A washing machine comprising a 130 frame, a washing receptacle, a plurality of plungers movable within said receptacle, a

pivoted platform mounted in said frame, a second platform resiliently mounted with respect to the pivoted platform, and driving means carried by the pivoted platform and connected with said plungers, said pivoted platform serving to cushion the action of the plungers within the washing receptacle.

3. In a washing machine, a frame, a washing receptacle carried thereby, a plurality of 10 guide elements mounted in the frame, reciprocating plungers mounted for vertical movement in said frame, a platform pivotally mounted in the frame, a second platform resiliently spaced from the first-mentioned platform, and driving means for said 15

plungers, said driving means being mounted upon said resiliently mounted platform, as and for the purpose set forth.

4. A washing machine comprising a frame, a washing receptacle, a plurality of 20 plungers movable vertically within said receptacle, a resilient pivoted platform mounted in said frame, and driving mechanism for said plungers, said driving mechanism being mounted upon said pivoted resilient platform whereby the driving mechanism and its support are movable relatively to said plungers. 25

HOMER METHOT.
